W. A. WILSON.
Watchman's Electric Register.
No. 239.076. Patented March 22, 1881.

Frank S. Parker

Inventor:

UNITED STATES PATENT OFFICE.

WILLIAM A. WILSON, OF NEEDHAM, ASSIGNOR TO JOSEPH H. ALDEN, OF BOSTON, MASSACHUSETTS.

WATCHMAN'S ELECTRIC REGISTER.

SPECIFICATION forming part of Letters Patent No. 239,076, dated March 22, 1881.

Application filed February 27, 1880.

To all whom it may concern:

Be it known that I, WILLIAM A. WILSON, of Needham, in the county of Norfolk and State of Massachusetts, have invented certain new and useful Improvements in Watchmen's Electric Registers; and I do hereby declare that the following, taken in connection with the drawings forming part of this specification, is such a full, clear, and exact description thereof as will enable others skilled in the art to make and use the same.

The nature of my invention consists, first, in so arranging the device by which the friction-rolls are held in place that the act of moving the rolls from or to their working place shall cause a temporary holding mechanism to come into action to prevent the paper from running down by its own gravity when not in use or leave it free to be drawn down by the rolls when in use; second, in an arrangement for moving the stylus in a right line across the paper without the use of guide-rods or a stylus-block, thus avoiding nearly all the friction of the ordinary instruments in use; third, in so arranging the train of wheels as to engage a stop-arm fastened to the armature-lever and acting directly upon the wheels, thus avoiding the use of intermediate mechanism; fourth, several minor improvements which will be fully set forth in the specification; fifth, constructing the instrument with a combined bed and back clock-plate, which, with the front clock-plate, will hold the registering and, if desirable, the time-clock movements in an immovable adjustment with the other parts, and also avoid the use of superfluous angles and parts liable to get out of order.

The devices may be best understood by reference to the specification and drawings, and are especially pointed out in the claims.

Referring to the drawings, Figure 1 is an elevation showing my device for moving the stylus across the paper, the stop-arm and the stop-pin acting with the armature-lever, and a front view of the friction-rolls and friction-springs and lever for holding or moving the rolls in place. Fig. 2 is a side elevation of the same, and shows the bent arm for holding the paper in place when not in use, also the general construction. Fig. 3 is a vertical cross-

section, showing in detail the mechanism for operating the friction-rolls and holding the paper in place. Fig. 4 is an enlarged view of the swinging stylus-arm, showing its perpendicular motion as the stylus moves across the paper.

In Figs. 2 and 3, E represents a strip of paper such as is used on instruments of this character with time-marks printed on its margin and extending downward through the guide G and back of the cross-bar F and between the friction-rolls D and H. These rolls are operated by a clock, from which motion is communicated to H through a gear-wheel on the shaft H', so regulated that the motion of the paper, as it passes over the stylus-point, shall be equal to the time-marks upon its margin, thus indicating the clock-time at which every puncture is made by the stylus.

In Figs. 1, 2, and 3, M represents an electromagnet, which, when in use, is put in circuit through the wires M', with a battery and a series of automatic circuit-closers of the ordinary character, each having its specific number of contact-points. The magnet M has an armature, A, fastened to a bent lever, A', hung on a fulcrum-shaft, A'', and having at its lower end a T-shaped piece, A³, from which the stop-arm A⁴ projects. The stylus B is fitted loosely in the end of the swinging arm B', having a slot in its lower end which slides upon the pivot B³, but being hung on the secondary arm B', which is pivoted to the angle B⁵, and is of such a length and pivoted at such a point on the long arm as will make the outside ordinates equal and cause the stylus to move across the paper in a right line. Affixed to the arm B' is a projecting catch, B⁶, which engages with the toothed wheel C. This toothed wheel is fixed on the shaft C', and is moved by a train of wheels operated by a weight or spring, and is held by a stop-pin, C², affixed to the wheel next in train to the shaft C'. The relation of the wheel on shaft C' to the pinion next in train is as seven to one, so that a revolution of the wheel with the stop-pin C² will turn the toothed wheel one-seventh round, or one tooth. The stop-pin C² engages with, and is in turn held by, the stop-arm A⁴. When an electric current is sent through the magnet M the ar-

mature A is drawn down and the lever A' throws the T-piece A³, and, disengaging the stop-arm A⁴, the wheel-train rotates the toothed wheel C, which, engaging with the projection B⁴, moves the swinging arm B' to the right, carrying the stylus B across the paper. During the journey of the stylus across the paper a distinguishing number of currents is sent by the circuit-closer and through the magnet operating the armature and angle and T-piece A³, which strikes the stylus B and thereby punctures the paper with the necessary number of marks. The circuit-closer being regulated to move with the wheel-train, the last current is transmitted before the wheel on which is the stop-pin C² has made a complete revolution, and, the lever A' being at rest, the stop-arm A⁴ is in place to engage with the pin C², which, when it comes round, is thus held in place ready for another record.

When not in use it is desirable to take off the pressure from the friction-rolls D, so that the paper may not run to waste; but in so doing, if not otherwise provided for, the paper, by its own gravity, runs down into the bottom of the case. To prevent this I have invented the holding mechanism shown in Fig. 3. D is the friction-roll, raised from the paper and hung by the shaft D⁵ to the springs D', which are affixed to the blocks and shaft D³, actuated by a hand-lever, D². Affixed to the same blocks and shaft D³ is a bent rod, D⁴. A movement of the lever D² moves all the parts simultaneously around the common central shaft, D³, and in moving the lever up I take the pressure of the rolls D, and at the same time press the bent rod or arm D⁴ against the paper E, pressing it against the cross-bar F and holding it in place, so that it will not run down. By pressing the lever D² down the friction-roll D is forced against the roll H and the paper is drawn down, as hereinbefore described. At the same time the bent arm D⁴ is thrown back, and, the paper no longer held against the cross-bar F, its motion is unimpeded.

By the use of the swinging arm B' and its compensating mechanism I avoid the use of the sliding stylus-block and guide-rods, which are objectionable, in that they cause useless friction, and, being operated by clock-work, are

easily got out of order by the dust and dirt gathering on their extended and exposed bearings, and by the rust which often gathers on the guide-rods.

In construction I use a bed-plate, K, to which are fastened the angles K² and K⁵ and the posts K⁴. To the posts K⁴ and the angles K² is fastened the front clock-plate, K', by the screws K⁶. Between the bed-plate K and the front plate, K', is placed the clock-work for registering, and, when not otherwise provided for, the time-clock also. The bed-plate thus answers the double purpose of holding the parts to one solid base and of a back clock-plate. The angles K⁵ are braced by the paper-guide G. By this construction I save the cost of many useless parts and get a simpler and stronger instrument, with every part easily accessible and more efficient than heretofore.

I claim—

1. In combination with the electric registering mechanism, the bent arm D⁴, pressure-rolls D, and lever D², acting on the paper F, substantially as described.

2. In an electric registering-instrument having a stylus operated by a magnet through an armature, a stylus-carrying device, which consists of a swinging lever, the movement of said lever being so compensated that the stylus moves in a straight, or nearly straight, line in traversing the paper.

3. In an electric registering-instrument, the combination of the magnet M, its armature A, and lever A' with the stylus-carrying device B' B² and stylus B, all arranged to operate together substantially as described, and for the purpose set forth.

4. In combination, the magnet M, armature A, and lever A', and stop-arm A⁴, with the stop-pin C², substantially as described, and for the purpose set forth.

5. The combination of the combined bed-plate and rear clock-plate, K, with the angle-piece K² and front clock-plate, K', substantially as described, and for the purpose set forth.

WILLIAM A. WILSON.
